(57) **CLAIM**

We claim the ornamental design for a circular food container, substantially as shown and described.

DESCRIPTION

FIG. 1 is a top perspective view of a circular food container showing our new design with the lid attached to the container; FIG. 2 is a top perspective view thereof with the lid separated from the container;

FIG. 3 is another top perspective view thereof with the lid attached to the container;

FIG. 4 is a side perspective view thereof;

FIG. 5 is another side perspective view thereof with the lid separated from the container;

FIG. 6 is a bottom perspective view thereof with the lid attached to the container;

FIG. 7 is a bottom aerial view thereof with the lid separated from the container;

FIG. 8 is a bottom plan view thereof;

FIG. 9 is a side elevation thereof with the lid attached to the container;

FIG. 10 is a top plan view thereof;

FIG. 11 is a side elevation view thereof with the lid separated from the container; and,

FIG. 12 is a cross-sectional view thereof with the lid attached to the container taken in the direction of line 12-12 as shown in FIG. 3.

The stipple shading shown in the drawings represents claimed texture.
